H. G. SCHWARZ
CLARIFIER AND THICKENER

1,704,993

Filed March 23, 1926

UNITED STATES PATENT OFFICE.

HENRY G. SCHWARZ, OF DENVER, COLORADO.

CLARIFIER AND THICKENER.

Application filed March 23, 1926. Serial No. 96,712.

This invention relates to clarifiers and thickeners for use in the separation of solids from liquids in liquid suspensions, and its primary object is to provide an apparatus of simple construction in which a clean separation of solids from liquid is effected by a settling action without the use of scrapers, rakes or other mechanical devices.

My invention is particularly adapted for use in sugar production to remove sugar lime from the waste waters obtained in the Steffens molasses desugaring process, or to separate the sugar juices from the lime sludge in the lime carbonate liquids of the carbonation system; and it has been demonstrated to provide an economical and highly efficient substitute for filter presses and mechanical thickeners heretofore used for the same purpose.

My invention is furthermore adapted for separating the clear sugar juice from limed pineapple juice or it may be used for clarifying cane juices, metallurgical slimes and any other material of similar nature.

My improved clarifier is distinguished by the production of an overflow of sparkling clearness, and it has in addition to a minimum cost of operation, the advantages of economical installation, small proportions in comparison with capacity, requiring smaller floor space than other apparatus used for the same purpose, and the elimination of expert attention required in all devices of similar type in which power driven mechanisms are employed for the separation of the thickened product.

A further aim of the invention resides in providing a clarification or thickening apparatus of the above described character which by simple variations in the proportions and angular arrangement of its parts may be readily adapted for each particular problem, and still other objects of the invention reside in details of construction and combinations of parts as will fully appear in the course of the following description.

In the accompanying drawings in which like characters of reference designate corresponding parts through the views;

Figure 1, represents a section through the device taken in a central vertical plane, and

Figure 2, an end-view partially in section, taken on the line 2-2, Figure 1.

Referring further to the drawings, the apparatus consists of a tank 5 having in-

clined sides terminating in one or more outlets at its bottom, an overflow for clear liquid near the top of one of its sides, and an inlet for material at an opposite side below the liquid level determined by the overflow.

It is desirable in the operation of the apparatus that the sides of the tank have a comparatively steep angle of inclination and in order to maintain this angle without reduction in the necessarily extensive length of flow line between the intake and the overflow and without the necessity of erecting the tank to an excessive height, I have divided the bottom portion of the tank into two compartments 6 of funnel shape, each 70 having an outlet 7 at its apex.

The space of the tank above the compartments is divided by longitudinally extending vertical baffle-plates 8 the principal function of which is to counteract turbulence of the inflowing material and promote an equable movement thereof to the point of overflow.

The tank is covered by a top plate 9 which may be slightly inclined from the intake side to the side of overflow-discharge for the main purpose of preventing obstruction to the flow of liquid by possible accumulation of scum or fibers.

In the middle of the top-plate is a dome 10 closed by means of a removable lid 12, through which scum may be removed from the surface of the liquid and by which access can be had to the interior of the tank.

The overflow outlets 13 of the tank open into a box 14 exteriorly of the same, which by means of an overflow-partition 15 is divided into two compartments 16 and 17. The compartment 16 directly connected with the overflow-openings 13 has a plurality of outlets 18 for the discharge of clear liquid into a receiver 20 and the other compartment has an outlet 19 for the scum which having risen to the level of the liquid in the compartment 16, passes across the partition 15.

The material entering the tank through an opening 21 in its top plate to which it is conducted by a pipe 22, is compelled to follow the inclination of the adjacent side of the tank, to a point at a distance below the liquid level determined by the overflow, by a vertical transverse weir 23 having a plurality of outlets 24, and thereby directs the solids in suspension toward the bottom of the tank. The liquid and finer solids travel 110

horizontally toward the outlet 13, the heavier than liquid solids settling gradually and the lighter solids and scum going to the top.

The discharge of thickened matter from 5 the outlets 7 in the bottom of the tank, is controlled by manually adjusted valves 25.

In the operation of the apparatus, the material enters the tank through the inlets 24 at a downwardly directed angle and is 10 forced to flow through the length of the tank at a velocity and under a pressure determined by the head of the feed, the openings in the discharge valves and other circumstances. It is preferred to regulate the 15 feed so that the tank is filled to its top plate at all times, whereby to maintain the material in the tank under slight pressure and prevent agitation.

The downward inclination of the feed as 20 it enters the tank, produces an initial quick separation of the heavier solids in suspension and during the following slow movement of the liquid to the point of overflow all other solids heavier than the liquid settle 25 gradually to the bottom of the tank while those lighter than the liquid rise to the surface in the form of a scum and are separated from the liquid either in the dome 10 or the compartment 17 of the receiving box 14. 30 The settling solids collected in the lower portions of the cone shaped compartments of the tank are discharged in liquid, through the outlets 7, the discharge being regulated and controlled by proper adjustment of the 35 valves 25.

It will thus be apparent that the separation of the solids from the liquid is obtained automatically, subject to a continuous feed and overflow, without the use of mechanical 40 appliances and without the expert attention required in other apparatus heretofore employed for similar purposes.

By shortening or lengthening the zone of the line of flow, determined by the length of 45 the tank between its points of intake and overflow, the apparatus may be constructed to meet practically any problem requiring a clean separation of liquids and solids in liquid suspensions.

50 The baffle plates dividing the flow zone in the upper portion of the tank into several compartments each having its separate intake opening and its separate overflow outlet, are instrumental in producing a slow 55 and equable flow of liquid through the zone and the box 14 which may be correspondingly divided by partitions 26, separates

from the overflow liquid any extraneous matter not collected in the dome 10.

The slightly inclined top prevents obstruction of the flow by accumulation of scum or fiber, and maintains the material in the tank under pressure, it having been found that in the treatment of the waste waters in a molasses desugaring process, a six inch head 60 of the waste waters preheated to from seventy-two degrees to seventy-five degrees Fahrenheit, gave a sparkling liquid of from 0.0 to 0.05% sugar content, although other conditions may require different heads and 70 temperatures.

Proper regulation of the valves controlling the outlets in the bottom of the tank, determines the grade of density of the sludge, which in practice, is preferably continuously conducted and, if necessary, may be accelerated by the use of pumps or spigots.

Having thus described my invention what I claim and desire to secure by Letters 80 Patent is:—

1. An apparatus of the character described comprising a tank with sides sloping to an outlet in its lower portion, having at opposite ends of a flow line in its upper portion an overflow and a feed intake, and having an inclined surface above the flow line, and a dome on said surface and between the intake and overflow for the removal of supernatant matter.

2. Apparatus of the character described, comprising a tank with sides sloping to an outlet in its bottom portion, having at opposite ends of a flow line in its upper portion, an overflow and a feed intake, a receiver connected with the overflow, a chamber separate from the receiver, and a partition between the receiver and the chamber providing an overflow for supernatant material, said receiver having an outlet for the discharge of clear liquid.

3. Apparatus of the character described, comprising a tank, partitions dividing the upper portion of the tank into unobstructed flow lines, the tank having a settling chamber below the flow lines, disposed to receive matter settling from the flow lines, each flow line having an overflow and a feed intake at opposite ends thereof, the intakes being entirely below the tops of the partitions.

In testimony whereof, I hereunto affix my signature.

HENRY G. SCHWARZ.
